THOMAS J. MURPHY, OF ROCHESTER, NEW YORK, ASSIGNOR OF ONE-HALF TO JAMES P. B. DUFFY, OF ROCHESTER, NEW YORK.

ALTERNATING-CURRENT MOTOR.

1,419,749.

Specification of Letters Patent. Patented June 13, 1922.

Application filed June 21, 1917. Serial No. 176,221.

To all whom it may concern:

Be it known that I, THOMAS J. MURPHY, a subject of the King of Great Britain, residing at Rochester, in the county of Monroe 5 and State of New York, have invented certain new and useful Improvements in Alternating-Current Motors; and I do hereby declare the following to be a full, clear, and exact description of the same, reference being had to the accompanying drawings, forming a part of this specification, and to the reference characters marked thereon.

My invention relates to alternating current motors and has reference particularly to a 15 type of construction coming within the general class of induction motors, wherein there is provided a stator affording a shifting magnetic field, acting upon a cooperating rotor, the movement of which is produced 20 by currents set up in it by the shifting magnetic field and reacting upon the field. The purpose of my invention is to provide a slow speed motor which can be retarded, speeded up, or reversed with great facility. Another 25 object of the invention is to afford a cheap construction, which is mechanically simple, so as to bring it within range of a large variety of applications where expensive motor installations and up-keep is prohibitive. 30 To these and other ends the invention consists in certain improvements and combinations of parts, all as will be hereinafter more fully described, the novel features being pointed out in the claims at the end of the 35 specification.

In the drawings:

Figure 1 is a sectional view illustrating one application of the invention, as an example of its possible uses, and

40 Figure 2 is a horizontal sectional view of Figure 1, largely diagrammatic, and illustrating the arrangement of circuits.

Similar reference characters throughout the several views indicate the same parts.

45 The invention may be carried out in a number of different ways and is susceptible of adoption for numerous purposes, and I have illustrated by way of example one of its large fields of usefulness, in the driving 50 operation of a record support or table in sound or music reproducing apparatus. In such instances, the motor can readily be designed for a speed such that no reduction gearing is necessary, the record being driven

at the same speed as the rotor. The present 55 structure eliminates the objectionable noise incidental to other forms of electrically driven sound reproducing apparatus, and moreover presents an exceedingly economical arrangement which can be easily adjusted to 60 suit changing requirements.

In the embodiment illustrated, 1 designates a stationary base or support upon which the field magnets are mounted, while 2 is a frame or spider which carries the rotor 65 and is fixed upon a spindle 3 journaled in a socket 4 of the base 1. The rotor consists of a relatively thin plate of diamagnetic material such as copper or aluminum, preferably in the form of a ring or annulus 5 70 which is carried upon the frame 2. In the present instance, the latter also constitutes the table or support for a disc record of a sound reproducing apparatus, although this forms no part of my invention, which may 75 be utilized for imparting movement to any driven member. The rotor 5 travels in a comparatively narrow gap that is afforded between two segmental laminated field magnets 6 constituting the stator, and which are 80 disposed upon opposite sides of the rotor and in close proximity to its opposite surfaces. The field magnets 6 may be laminated and radially slotted and are adjustable with reference to each other, but normally 85 disposed in staggered relation to each other so that the teeth or projections of one magnet are directly opposite the winding spaces or slots of the opposite magnet. To this end the outer magnet is held in place by the 90 bolts 7 cooperating with slots 8 so that by moving the bolts lengthwise of the slots, the outer stator unit or field magnet can be brought into varying relation with the inner or opposite magnet, and under ordinary operating conditions, one magnet is positioned 95 with reference to the other substantially as shown in Figure 2, the purpose of which will appear in a moment.

With the parts arranged as described, alternating current is fed to the field magnets, so as to present the maximum intensity first upon one side of the rotor and thereafter upon the other side, through the alternating poles, and the current set up in the rotor reacts upon the field magnets in such a way as to have imparted to it a series of successive impulses producing a continuous

movement. To effect this, there is produced a difference in phase of magnetic flux from the two field magnets, and this may be accomplished in different ways. As an illustration of one efficient method of accomplishing it, I have shown a resistance element R , which is non-inductive and arranged in parallel across the circuit leading to one of the field magnets. The circuit is 10 designated generally at C , being supplied from any suitable source of alternating current, which passes by conductor C' to the outer field magnet, thence by conductor C^2 to the resistance element R and to the inner 15 field magnet, and from there through conductor C^3 to the other side of the line. Thus the phase of the current in one magnet is displaced with reference to that in the other, so that in passing through the one magnet 20 it lags somewhat behind the other. This may also be accomplished by employing a two-phase current for the different magnets, or by using ferric metals of different hysteresis losses for the inner and outer magnets. Also the windings may be different on 25 the inner and outer magnets, to increase the difference in phase of the magnetizing current, or one magnet may be provided with greater self induction than the other, as by 30 partially or entirely closing the radial slots at the outer edge. And to obtain increased motive power, the stator may include com-

plete rings, instead of segmental magnets as herein shown.

By adjusting the outer field magnet with 35 reference to the inner one, the speed of the rotor can be reduced until the poles of one magnet are exactly opposite the poles of the other, at which point no movement will take place and if the adjustment is carried still 40 further, the effect is to move the rotor in the opposite direction from its previous direction of travel and thus reverse the motor. By the adjustment of the outer field relative to the inner if the electrical phase displacement in the inner and outer windings be regarded as constant then the synchronous speed of the motor is changed.

I claim as my invention:

1. An induction motor comprising an annular rotor, field magnets disposed on opposite sides thereof having cores of metals characterized by different hysteresis losses for producing a shifting field, and adjustable means for varying the relative positions 55 of said magnets and thereby controlling the speed of rotation of said rotor.

2. An induction motor comprising a rotor movable between oppositely arranged field magnets, the magnets on opposite sides of 60 the rotor comprising laminae of metals having different hysteresis losses.

THOMAS J. MURPHY.
